DESIGN FOR A RING MOUNTING

William H. Rothe, Irvington, N. J.

Application June 21, 1939, Serial No. 85,601

Term of patent 3½ years

To all whom it may concern:

Be it known that I, William H. Rothe, a citizen of the United States, residing at Irvington, in the county of Essex and State of New Jersey, have invented a new, original, and ornamental Design for a Ring Mounting, of which the following is a specification, reference being had to the accompanying drawing, forming part thereof.

In said drawing:

Fig. 1 is a side elevational view of a ring mounting showing my new design;

Fig. 2 is a top plan view thereof; and

Fig. 3 is an edge view.

I claim:

The ornamental design for a ring mounting, as shown.

WILLIAM H. ROTHE.
